UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,073, dated September 9, 1902.

Application filed July 29, 1902. Serial No. 117,592. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part of this specification, in which the invention is illustrated in front elevation.

The leading features of my design consist in a frame each of the sides of which shows in relief an ornamental column surmounted by a human head. The top piece, which is in the shape of a hood, has an ornamented upper edge, a central shell-like device, and open lattice-work extending from the shell and rest-

ing on the heads at the tops of the side columns. The center or summer front depicts a summer-garden scene, the central figures of which are a girl seated in a swing and a young man in the act of impelling the swing forward. The swing depends from the branches of two trees surrounded by shrubbery. In the background of the picture is a lattice-work arch entwined with flowers and foliation.

I claim—

The ornamental design for a fireplace-front as herein described and shown.

In testimony whereof I have hereunto set my hand.

THOMAS M. DUDGEON.
